ROD BENDING MACHINE

Roy M. Eidal, Albuquerque, N. Mex.

Application April 3, 1952, Serial No. 280,258

10 Claims.

(Cl. 153—20)

1

This invention pertains to improvements in rod bending machines, and is particularly directed to an improved machine for effecting a plurality of multiple bends in rods used for forming bar joist structures and the like.

One of the objects of this invention is to provide a machine for automatically forming a plurality of bends or kinks along a rod structure in a highly efficient rapid and accurate manner.

Still another object of this invention is to provide a rod bending machine capable of taking straight bars and with a single longitudinal movement bend said bar into a series of angular positions accurately spaced longitudinally of the finished bar structure.

Still another object of this invention is to provide a bar bending machine adapted to take a series of bars or straight rods and bend them automatically into a plurality of angularly disposed portions in an automatic and continuous rapid manner while at the same time providing the finished structure with accurately bent and positioned portions.

And still another object of this invention is to provide a rod bending machine having a plurality of bending links mounted on a longitudinal slide structure which initially support one or more straight rods or bars at the beginning of the operating cycle and which is operated by tension on a main draw cable for progressively and automatically effecting a plurality of bends in the rod structure at the completion of the operating cycle.

Further features and advantages of this invention will appear from a detailed description of the drawings in which:

Fig. 1 is a plan view of a rod bending machine incorporating the features of this invention.

Fig. 2 is a side elevation of the rod bending machine shown in Fig. 1.

Fig. 3 is an enlarged fragmentary plan view showing the position of the linkage and workpiece at the beginning of the operating cycle.

Fig. 4 is an enlarged plan view similar to Fig. 3, but showing the position of the operating linkage at the completion of the rod bending operation.

Fig. 5 is a transverse section on the line 5—5 of Fig. 4.

Fig. 5a is a transverse section on the line 5a—5a of Fig. 4.

Fig. 6 is a diagrammatic view showing the position of the work and bending anvils at the beginning of the operating cycle.

Fig. 7 shows the condition of work and bending anvils at one of the initial stages of operation of the machine.

2

Fig. 8 is a diagram showing a second condition of operation with the bending work partially completed.

Fig. 9 is a diagram showing the final position of work and bending anvils at the conclusion of the bending operation.

Fig. 10 is an illustration of a typical bar joist utilizing the bent rod structure provided by the rod bending machine.

10 Fig. 11 is a cross section on the line 11—11 of Fig. 10.

As illustrative of one embodiment of this invention, there is shown a rod bending machine having a main frame consisting of a pair of longitudinal channel irons 15 which are suitably supported rigidly on a plurality of upstanding legs 16 connected together by suitable tie rods 17. On the top surfaces 18 of the channel irons 15 are rigidly fixed two rectangular longitudinal bar members 19 spaced apart to form a longitudinal slot 20 by the surfaces 21 of the bar members 19. A suitable finished work receiving rack 22 may be provided if desired to one side of the longitudinal bar members 19 and slot 20.

25 To one end of the bars 19 there is rigidly clamped a block 23 which is held in place by suitable T-slot bolts or the like 24 passing thru the slot 20 and having nuts 25 for adjustably clamping the block 23 in desired position on the bars 19. An adjustable block 26 may also be positioned on the bar member 19 having a stop abutment surface 27 and held in place in the slot 20 by a usual bolt and nut indicated at 28. A side stop piece 36a is also fixed on the block 23 to hold the end of the work W in proper alignment during the bending operation. Pivotally mounted on a suitable pin 29 fixed in the block 23 is a link 30 which is connected at its outer end thru a pin 31 to a bell crank link 32. The bell crank link 32

30 is pivotally mounted on a pin 33 which has a portion 34 nicely sliding between the surfaces 21 of the slot 20 between the members 19 and also a head portion 35 on its underside to hold it in proper position slidably in the slot 20 at all times.

40 A second link 30a is also pivotally mounted around the same pin 33, Fig. 5, as is the link 30 around the pin 29. Fixed to the link 30 is the work engaging anvil piece 36 which has a work engaging edge 37 preferably located substantially on the axis of the pin 29. Work engaging anvil piece 38 is fixed on the bell crank link 32 with its work engaging edge 39 located substantially on the axis of pivoting of the pin 31 while another work engaging anvil piece 40 is fixed on the bell crank link 32 with its work engaging edge 41 located substantially on the axis of pivoting of the

pin 33. All of the work engaging anvil pieces 36, 38 and 40 may be adjustably mounted on their respective links if desired for precise setting and for varying the depth of bends to be made in the workpiece bar or rod W.

A cable pulley 42 is journaled on a stud 43 fixed in the bell crank link 32 closely adjacent to the pivot pin 33 while a second cable pulley 44 is journaled on a stud 45 fixed in the outer end of the bell crank portion of the lever 32 as best seen in Figs. 3 and 4. There is also provided a stop member 46 which is fixed to the link 30 or 30a and the like having an abutment surface 47 adapted to engage the abutment surface 48 of the bell crank link 32 so as to limit the swinging motion of the bell crank lever 32 toward the links 30 or 30a. It is understood that the member 46 could be made adjustable on the link 30 to vary this relative swinging movement.

A whole series of links 30, 30a, 30b, etc. and links 32, 32a, etc., the number depending on the desired number of bends to be made in the work W, may be provided each constructed as described for the links 30 and 32 above. Each of the sets of links are interconnected as best shown in Figs. 3 and 4 thru pivot pins such as 33 which are slidably mounted in the slot 20 between the members 18 as described.

A main operating or draw cable 49 is threaded over the pulleys 42 and 44, the cable 49 passing over the pulley 42 between the work W and the pulley, and passing over the outside of the pulley 44 away from the work W, as best seen in Figs. 3 and 4. The outer end of the cable is connected by a suitable eyelet 50 to a stud 51 fixed to the last bell crank lever 32X as best seen in Figs. 3 and 4 at a point similar to the studs 43 in the other bell crank lever links. The opposite end or takein end of the draw cable 49 is wrapped around a winch drum 52, Fig. 1, which drum is driven by suitable winch mechanism and motor indicated generally at 53 in a well known manner. A second return cable 54 is also attached around the stud 51 in a suitable manner and operates over a winch drum 55 driven by a suitable winch and motor 56 on the opposite end of the draw bench members 49, as best seen in Fig. 1.

The operation of the rod bending machine is substantially as follows:

The workpiece comprising a rod or bar W is placed in the machine as best seen in Figs. 3 and 6 with the work contacting anvil 36 and anvil 40 to one side of the bar, and with the work contacting anvils 38 on the opposite side of the bar. With all of the links in stretched out position as effected by operating the winch 55 and return cable 54, the bar may preferably be positioned endwise by abutment of its end 57 with the abutment surface 27 of the stop piece 26, sufficient extra length being allowed on the work to take care of all of the bends as the work is operated upon. The operating or draw winch 52 is then energized thru its motor 53 to cause the draw cable 49 to be pulled, to the right in Figs. 3 and 4. As this cable 49 is drawn in, the first thing that happens is that the bell crank link 32, Fig. 3, pivots around its pin 33 causing the pulley 44 and stud 45 to rock in the direction indicated by the arrow 58 which causes the outer end of the bell crank link 32 and the work engaging anvil 38 to swing in the direction indicated by the arrow 59 so as to begin bending of the bar as shown in Fig. 7, the swinging motion in the direction of the arrow 59 continuing until the

abutment surface 47 on the stop piece 26 on the link 30 engages the surface 48 of the bell crank link 32 as described and as best seen in Fig. 4. Thus the first bend is made in the bar W. Continued application of pulling power on the cable 49 causes subsequent links 32a-32a etc. up thru 30X and 32X, Figs. 3 and 4, to assume the positions shown in Fig. 4 to thus bend the bar as shown in Figs. 8 and 9 into a plurality of kinked positions accurately located relative to one another and automatically by the continued application of pulling power to the cable 49. The aforementioned progressive operation is automatically effected by the interaction of the workpiece on uniquely arranged machine parts. It is to be understood that any number of bars can be bent simultaneously by making the anvil pieces 36, 38 and 40 of sufficient height and laying several bars as desired one on top of the other during the bending operation. At the conclusion of the bending operation, as shown in Fig. 9, the winch 55 is stopped and the slight spring and tension in the mechanism and in the bars being bent automatically releases sufficient tension to allow the bars to be loosely picked up from the apparatus in the position shown in Fig. 4. The bars thus prepared as shown at Wa in Fig. 10 are then welded to suitable angle pieces 60 to form the well known bar joist of commercial use.

To put the machine ready for operation again for the next set of bending operations the return winch 55 operated by its motor 56 is then energized to pull all of the linkages back to straight position, as shown in Fig. 3 ready for receipt of another set of bars as shown in Figs. 3 and 6 and the repetition of the aforementioned bending cycle.

While the apparatus herein disclosed and described constitutes a preferred form of the invention, any suitable means may be utilized to actuate the cables 49 and 54. It is also to be understood that the apparatus is capable of mechanical alteration without departing from the spirit of the invention and that such mechanical arrangement and commercial adaptation as fall within the scope of the appendent claims are intended to be included herein.

Havink thus fully set forth and described this invention what is claimed as new and desired to be obtained by the United States Letters Patent is:

1. In a rod bending machine having a frame, a pair of guide bars forming a longitudinal guide slot on said frame, a series of links pivotally interconnected at their outer ends, means for pivotally mounting one end of said series of links on a pivot fixed to said frame, means for slidably mounting every other one of said interconnecting pivots for longitudinal movement in said slot, a pull out cable connected to the opposite end of said series of said links from said pivot fixed on said frame, and a draw cable fixed to said opposite end of said series of links, cable pulley means on every other one of said links operatively engaged by said cable to cause said links to fold together, power means on said frame to pull said draw cable, and work engaging anvils on said every other one of said links arranged to alternately engage each side of a workpiece to be bent in said machine so that said workpiece automatically causes progressive bends to be formed therein upon actuation of said draw-cable.

2. In a rod bending machine having a frame,

a pair of guide bars forming a longitudinal guide slot on said frame, a series of links pivotally interconnected at their outer ends, means for pivotally mounting one end of said series of links on a pivot fixed to said frame, means for slidably mounting every other one of said interconnecting pivots for longitudinal movement in said slot, a pull out cable connected to the opposite end of said series of said links from said pivot fixed on said frame, and a draw cable fixed to said opposite end of said series of links, cable pulley means on every other one of said links operatively engaged by said cable to cause said links to fold together, power means on said frame to pull said draw cable, work engaging anvils on said every other one of said links arranged to alternately engage each side of a workpiece to be bent in said machine so that said workpiece automatically causes progressive bends to be formed therein upon actuation of said draw cable, and stop means interacting between pairs of links to individually limit relative pivotal movement of said links.

3. A rod bending machine comprising a frame, a fixed pivot pin on one end of said frame, a pivot pin arranged for longitudinal sliding movement on said frame, a first link pivotally connected at one end to said fixed pivot, a bell-crank link having one arm pivotally connected at its outer end to the other end of said first link and pivotally connected at its intermediate point to said slidable pivot pin, a stud fixed in the outer end of the other arm of said bell-crank link, a cable roller journaled on said stud, a draw cable fixed to said bell-crank link at its intermediate point of pivotal mounting and passing over said cable roller on the side of said cable roller opposite from the pivotal connection between said links, and power means for pulling said draw cable and moving said slidable pivot pin toward said fixed pivot, an anvil piece fixed on said first link at its connection with said fixed pivot, anvil piece fixed on said bell-crank link at its intermediate pivotal connection, and an anvil piece fixed on one of said links at the pivotal connection between said links.

4. A rod bending machine comprising a frame, a fixed pivot pin on one end of said frame, a pivot pin arranged for longitudinal sliding movement on said frame, a first link pivotally connected at one end to said fixed pivot, a bell-crank link having one arm pivotally connected at its outer end to the other end of said first link and pivotally connected at its intermediate point to said slidable pivot pin, a stud fixed in the outer end of the other arm of said bell-crank link, a cable roller journaled on said stud, a draw cable connected to said bell-crank link at its intermediate point of pivotal mounting and passing over said cable roller on the side thereof opposite from the pivotal connection between said links, power means for pulling said draw cable and moving said slidable pivot pin toward said fixed pivot pin, a work engaging anvil fixed on said first link, a work contacting edge on said work engaging anvil lying substantially on the axis of said fixed pivot pin and facing toward said cable, and oppositely facing work contacting anvils on said bell-crank link comprising, a work contacting edge lying substantially on the axis of said sliding pivot pin and facing toward said cable, and a work contacting edge lying substantially on the pivotal connection between said links and facing away from said cable.

5. A rod bending machine comprising a frame,

a fixed pivot pin on one end of said frame, a pivot pin arranged for longitudinal sliding movement on said frame, a first link pivotally connected at one end to said fixed pivot, a bell-crank link having one arm pivotally connected at its outer end to the other end of said first link and pivotally connected at its intermediate point to said slidable pivot pin, a stud fixed in the outer end of the other arm of said bell-crank link, a cable roller journaled on said stud, a draw cable connected to said bell-crank link at its intermediate point of pivotal mounting and passing over said cable roller on the side thereof opposite from the pivotal connection between said links, power means for pulling said draw cable and moving said slidable pivot pin toward said fixed pivot pin, a work engaging anvil fixed on said first link, a work contacting edge on said work engaging anvil lying substantially on the axis of said fixed pivot pin and facing toward said cable, and oppositely facing work contacting anvils on said bell-crank link comprising, a work contacting edge lying substantially on the axis of said sliding pivot pin and facing toward said cable, and a work contacting edge lying substantially on and facing away from said cable, the pivotal connection between said links, and stop means fixed intermediate the ends of said first link having an abutment surface facing toward said cable and engaging said bell-crank link adjacent said cable roller to limit relative movement of said slidable pivot pin toward said fixed pivot pin.

6. A rod bending machine comprising, a frame, a fixed pivot on said frame, a series of pivotally interconnected links having one end connected to said fixed pivot, means for slidably mounting every other pivotal connection between said links on said frame, a pull-out cable connected to the other end of said series of links, power means for pulling on said pull-out cable to stretch out said series of links in a straight line, bell-crank arm portions on every other one of said links in said series, cable pulleys journaled on the outer ends of said bell-crank arm portions, further cable pulleys journaled on said links having said bell-crank arm portions substantially at the pivotal connection of each of said bell-crank arm portions with the adjacent link, a draw cable fixed to the outer end of the last of said series of links and passing over said pulleys so as to cause said links to fold together and said sliding pivots to move toward said fixed pivot, oppositely facing work engaging anvils fixed on said links adjacent their pivotal connections, and power means for pulling said draw cable.

7. A rod bending machine comprising, a frame, a fixed pivot on said frame, a series of pivotally interconnected links having one end connected to said fixed pivot, means for slidably mounting every other pivotal connection between said links on said frame, a pull-out cable connected to the other end of said series of links, power means for pulling on said pull-out cable to stretch out said series of links in a straight line, bell-crank arm portions on every other one of said links in said series, cable pulleys journaled on the outer ends of said bell-crank arm portions, further cable pulleys journaled on said links having said bell-crank arm portions substantially at the pivotal connection of each of said bell-crank arm portions with the adjacent link, a draw cable fixed to the outer end of said series of links and passing over said pulleys so as to cause said links to fold together and said sliding pivots to move toward said fixed pivot, oppositely facing work en-

gaging anvils fixed on said links adjacent their pivotal connections; power means for pulling said draw cable, stop pin means on every other one of said series of links arranged to engage each of said bell-crank portions to limit movement of each of said sliding pivots on said frame.

8. A rod bending machine comprising, a frame, a fixed pivot on said frame, a series of pivotally interconnected links having one end connected to said fixed pivot, means for slidably mounting every other pivotal connection between said links on said frame, a pull-out cable connected to the other end of said series of links, power means for pulling on said pull-out cable to stretch out said series of links in a straight line, bell-crank arm portions on every other one of said links in said series, cable pulleys journaled on the outer ends of said bell-crank arm portions, further cable pulleys journaled on said links having said bell-crank arm portions substantially at the pivotal connection of each of said bell-crank arm portions with the adjacent link, a draw cable fixed to the other end of said series of links and passing over said pulleys so as to cause said links to fold together and said sliding pivots to move toward said fixed pivot, power means for pulling said draw cable, work engaging anvils on said links having said bell-crank arm portions having work engaging ends facing in a direction toward said bell-crank arm portions and lying substantially on the axis of said slideable pivot pins and said fixed pivot pin, and further work engaging anvils having work engaging ends facing in a direction away from the outer ends of said bell-crank arm portions and lying on the axis of pivotal interconnection of said links other than said sliding and fixed link pivotal connections.

9. In a rod bending machine, a frame, means for supporting a rod to be bent on said frame comprising a series of pivotally interconnected links, a series of longitudinally disposed work en-

gaging anvils alternately presented on each side of the workpiece when placed in said machine, and means for successively actuating said links under the control of the workpiece being bent so as to progressively move alternate work engaging anvils to one side of the workpiece against the work and between work engaging anvils on the opposite side of said workpiece.

10. In a rod bending machine, a frame, means for supporting a rod to be bent on said frame comprising a series of pivotally interconnected links, a series of longitudinally disposed work engaging anvils alternately presented on each side of the workpiece when placed in said machine, and means for successively actuating said links from the workpiece being bent so as to progressively move alternate work engaging anvils to one side of the workpiece against the work and between work engaging anvils on the opposite side of said workpiece, and means for progressively moving each alternate work engaging anvil between pairs of anvils on opposite sides of said work in response to the bent condition of the workpiece so as to automatically complete the progressive bending operation of a series of links in the work to be operated upon.
